UNITED STATES PATENT OFFICE

PRESTON E. GILLING, OF EAST ORANGE, NEW JERSEY, ASSIGNOR TO RADIO CONDENSER COMPANY, OF CAMDEN, NEW JERSEY

ELECTRICAL CONDENSER

Application filed February 26, 1925. Serial No. 11,852.

This invention relates to an electrical condenser in which a stack of alternate layers of mica and metal foil are built up and held between a pair of binding or bolster plates 5 through the medium of clamping members which engage, not only the binding members, but the ends of the metal foil which have alternate layers brought out at the opposite ends of the condenser stack. 10 The condenser stack per se, may be constructed in any suitable manner such as that described in Van Deventer Patent 1,181,623 issued May 2, 1916, or in the application of Harry A. Hatch, Serial No. 417,347 filed 15 October 16, 1920, now Patent 1,574,424, issued February 23, 1926.

The condenser herein disclosed is particularly adapted for use in connection with radio circuits and apparatus, although it is 20 to be understood that it is not limited exclusively to this kind of use.

In the Van Deventer, and Hatch patents above referred to, certain types of clamping terminals are shown and described. The 25 clamping means herein disclosed is materially different from the clamping terminals of said patents and application referred to, or other prior art, as will be hereinafter pointed out.

30 Fixed condensers used in radio receiving circuits are usually of relatively low capacity; consequently the number of metallic conducting plates or elements forming the condenser stack is relatively few; in fact, 35 for very low capacity condensers only one pair of plates of suitable area need be used. In a condenser of this character, it is one of the objects to utilize the conducting plates for a number of purposes thereby simplifying and cheapening not only the cost of 40 the condenser, but reducing the time required to connect it into a radio circuit.

Other objects will be apparent to one skilled in this art after a study of the 45 specification taken in connection with the annexed drawing wherein

Figure 1 is a plan view of my improved condenser showing a grid lead mounted thereon.

50 Figure 2 is a side view of Fig. 1.

Figure 3 is a view of the right hand end of Fig. 1.

Figure 4 is a sectional view on the lines 4-4 of Fig. 1.

In the various figures, 1 and 2 are binding or bolster members preferably of good stiff insulating material and between these members is positioned the condenser elements or conducting plates separated by suitable dielectric material such as mica—such a group of elements are illustrated by 3 in Fig. 4, the outer elements or conducting plates of the stack are preferably of thicker material as indicated by the numbers 4 and 5, which plates are formed with arms 6 and 7 terminating in ends suitable to receive a high resistance unit 8, commonly referred to as a grid leak. Each of the arms 6 and 7 have formed integral therewith, a spring tongue 9 so as to produce an eyelet 10 through which a conductor may be passed thereby and gripped by the resilient or spring tongue 9, thus making contact with each of the elements 4 and 5 of the condenser or with other properly associated elements 3. In some cases, I may form lugs 11 and 12 on the conducting plates 4 and 5 respectively, which lugs may each have a hole 13 therein for the purpose of mounting the condenser when it is not desired to slidably mount it on the conductor or bus-bar by means of the spring tongue 9, or eyelet 10, as just described. Each of the lugs 11 and 12 may also be provided with an ear 14 to which a conductor may be soldered or otherwise fastened thereto. Of course it is to be understood that where the lugs 11 and 12 are used for mounting the condenser, proper consideration must be given to insulating these lugs in any suitable manner so that the condenser will function. As a means for holding the binding or bolster members 1 and 2 in position, the conducting plates 4 and 5 are provided with clamping fingers 15 which pass over the edge of the plates 4 and 5 and are bent downward over the outer surfaces thereof. From the construction just described it will be clear, that the conducting plates 4 and 5 serve several purposes, first they act as the capacity elements 100

of the condenser, secondly they are provided with means which are the fingers 15, for clamping the condenser stack together, and being provided as they are with arms 6 and 7, they serve as direct supporting means for the grid leak, at the same time, the arms 6 and 7 are so constructed that the conductors may be quickly attached or detached to or from them. Furthermore these plates 4 and 5 are of sufficient rigidity so that the condenser may be mounted directly therefrom, without further supporting means. In some cases I may use a metal clamp 16 passing over one of the bolster members and locking on the other as is clearly shown in Fig. 1. When the metal clamp 16 is used, I prefer to furnish it with a central opening 17 and likewise the clamping members 1 and 2 and the conducting plates 4 and 5 as well as the other elements of the condenser if they are used, so that a mounting screw may be passed through the hole or opening 17. This sort of mounting has some advantage in that the screw tends to bind the condenser together at the central portion. The clamping member 16 may also be provided with lugs similar to 11 and 12 for the purpose of mounting the condenser and it is therefore clearly apparent that the various details for carrying my invention into practice may be varied considerably without departing from the spirit of the invention or the scope of the appended claims.

Having thus described my invention what I claim is:

1. An electrical condenser comprising a plurality of conducting plates separated by dielectric plates, a pair of binding members and means integral with at least one pair of said conducting plates for clamping said binding members in position.
2. An electrical condenser comprising at least one pair of conducting plates separated by a dielectric, a pair of binding members and means integral with said conducting plates for clamping said binding members for the purpose described.
3. An electrical condenser comprising at least one pair of conducting plates separated by a dielectric, a pair of binding members, means including clips integral with said conducting plates for engaging said binding members to hold them in position, means integral with said plates for making connections thereto and means integral with each plate for mounting a shunt across said plates.
4. An electrical condenser comprising at least one pair of conducting plates separated by a dielectric, a pair of binding members, means including clips integral with said conducting plates for engaging said binding members to hold them in position, said plates having means formed integral there-

with to act as connecting means for a conductor and also having further integral means for mounting a resistance device thereon.

5. An electrical condenser comprising at least one pair of conducting plates separated by a dielectric, a pair of binding members, lugs integral with each of said pair of plates for making direct connection thereto, additional lugs on said plates for mounting a relatively high resistance conductor, and means including parts integral with said plates for clamping said binding members securely together.

6. An electrical condenser comprising at least one pair of conducting plates separated by a dielectric, a pair of binding members, a plurality of lugs integral with each of said pair of plates, at least one of said sets of lugs having conductor attachment means and one set of lugs having means for carrying a shunt resistance, and means including lugs integral with said plates for clamping the binding members in position.

7. An electrical condenser comprising at least one pair of conducting plates separated by a dielectric, said conducting plates being of sufficient rigidity so that the condenser may be mounted therefrom; lugs integral with and extending from said plates, by which the condenser may be mounted, a pair of binding members for the condenser and means including members integral with said plates for holding said binding members securely in position.

In testimony whereof, I affix my signature.

PRESTON E. GILLING.
